US0D1113839S

(12) **United States Design Patent** (10) **Patent No.:** **US D1,113,839 S**
(45) **Date of Patent:** **** Feb. 17, 2026**

(54) **REMOTE CONTROL**

(71) Applicant: **HONG KONG TIMTOM TECHNOLOGY CO., LIMITED,**
Hong Kong (CN)

(72) Inventor: **Canqun Jing**, Shenzhen (CN)

(73) Assignee: **HONG KONG TIMTOM TECHNOLOGY CO., LIMITED,**
Hong Kong (CN)

(**) Term: **15 Years**

(21) Appl. No.: **29/950,740**

(22) Filed: **Jul. 4, 2024**

(30) **Foreign Application Priority Data**

Jun. 14, 2024 (CN) 202430364967.2

(51) **LOC (15) Cl.** **14-03**

(57) **CLAIM**

The ornamental design for a remote control, as shown and described.

DESCRIPTION

FIG. 1 is a front, left and bottom perspective view of a remote control, showing my new design;

FIG. 2 is a rear, right and top perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

The broken lines shown in the drawings illustrate portions of the remote control that form no part of the claimed design.

1 Claim, 8 Drawing Sheets
